Specification for Design.

Patented Nov. 15, 1910.

Application filed August 15, 1910. Serial No. 577,383. Term of patent 7 years.

To all whom it may concern:

Be it known that I, EUGENE H. HILL, a citizen of the United States, residing at No. 179 West Huntingdon street, in the city and county of Philadelphia and State of Pennsylvania, have invented a new, original, and ornamental Design for Rugs, of which the following is a specification, reference being had to the accompanying drawing, forming part thereof.

The drawing is a view of a rug having my design, the design being shown in full for somewhat more than one-quarter section and in outline for the remainder of the rug.

I claim:

The ornamental design for a rug, as shown.
